M. D. CHURCH,
SYSTEM OF ENGINE CONTROL,
APPLICATION FILED MAR. 31, 1920.

1,354,886.

Patented Oct. 5, 1920.

UNITED STATES PATENT OFFICE.

MAYNARD D. CHURCH, OF HARTFORD, CONNECTICUT, ASSIGNOR TO THE TERRY STEAM TURBINE COMPANY, OF HARTFORD, CONNECTICUT, A CORPORATION OF CONNECTICUT.

SYSTEM OF ENGINE CONTROL.

1,354,886.

Specification of Letters Patent.

Patented Oct. 5, 1920.

Application filed March 31, 1920. Serial No. 370,089.

To all whom it may concern:

Be it known that I, MAYNARD D. CHURCH, a citizen of the United States, and a resident of Hartford, county of Hartford, State of Connecticut, have invented certain new and useful Improvements in Systems of Engine Control, of which the following is a specification.

In my co-pending application S. No. 336,724 filed November 8th, 1919, I have described an arrangement where the power of a steam engine, such as a steam turbine, may be used for driving purposes and the exhaust steam for heating or other useful purpose, and a system of control whereby variations in the relation between the amount of exhaust steam and the demand for exhaust steam automatically adjust the speed setting of the governor or other speed controlling device of the steam engine. In that application, I describe, as showing among other forms which the invention may take, two illustrative embodiments, one wherein the demand for exhaust steam is manifested by pressure variations, and the other wherein the demand is manifested by temperature variations.

The present application is in the nature of a division of the above mentioned application in that it is directed particularly to the system of control wherein variations in temperature of the exhaust steam itself or of a substance heated wholly or in part thereby manifest the extent of the demand for exhaust steam and affect adjustment of the speed setting of the governor.

In the accompanying drawing,

The figure is a layout more or less diagrammatic of an installation in which the present invention is incorporated.

Referring to the drawing, *a* is the primary driver such as an electric motor; *b* is the driven member such as an exciter, and *c* is a steam engine such as a turbine, all of which may be connected to the shaft of a generator so that when the motor drives the exciter it will also drive the rotor of the turbine, and *d* is a tank having a water heater *h* to which the exhaust line 10 of the steam turbine leads.

The steam engine *c* may be of any suitable kind, that shown in the drawings being a turbine of the well known Terry type. It has a steam supply to the usual valve chamber 11 in which is located the inlet valve

12, the stem of which is connected as shown to one end of the lever 13 pivoted as at 14. On the main shaft 15 of the turbine is a speed regulator such as a centrifugal governor which may be of any desired construction. The governor shown in the drawings is of a well known type having a plunger 16 rotatable with but longitudinally movable of the main shaft 15; a pair of weighted L-shaped arms 17 pivoted on a disk 18 fixed to the shaft 15 and engaging at their inner ends against the end of the plunger 16; and a spring 19 normally urging the plunger against the inner ends of the weighted arms 17. The outer end of the plunger 16 is connected, as shown, to a lever 13. It will be understood that when the speed of the turbine shaft 15 increases, the outer ends of the arms 17 will swing away from each other, thereby causing the inner ends of these arms to move the plunger 16 outwardly against the compression of the spring 19, the result being that the lever 13 is rocked in a direction to move the valve 12 toward its seat and reduce the amount of steam supply to the turbine. When the speed of the shaft 15 decreases, the reverse action takes place.

By the present invention, the governor of the turbine is supplemented by mechanism responsive to variations in temperature affected, either directly or indirectly, by variations in the relation between the amount of exhaust steam from the turbine and the demand for such steam. In the present instance, I have shown the exhaust steam line 10 of the turbine *c* leading to the tank *d* containing a substance the temperature of which is to be maintained within certain limits. Whether the steam is discharged into the tank or passed through a closed heating element in contact with the fluid in the tank is immaterial. Variations in the temperature of this substance are rendered effective in controlling the speed setting of the governor through the instrumentality of a temperature responsive device of any suitable type but herein shown as being in the form of a bulb 21 containing a volatile liquid, such as ether, this bulb being located within the tank and connected by means of a small tube 22 to a chamber 23 of a pressure responsive device. The chamber of the pressure responsive device is formed in part by a collapsible diaphragm 24 loaded

with a spring 25 positioned between the dia-
phragm and an adjustable nut 26 carried
by the frame of the regulator. Movement
of the diaphragm 24 is communicated to the
lever 13 by means of a tension spring 27 con-
nected at its inner end by a rod 28 to the
head of the diaphragm and at its outer end
by a rod 29 to the lever 13. The outer end
of the rod 29 is threaded to receive a nut 30
10 to permit of manual adjustment of the ten-
sion of spring 27. The control may also be
manually adjusted by regulating the nut 26
20 to vary the load upon the diaphragm 24.

The pressure regulator is first set by ad-
15 justing the nuts 30 and 26 so that the speed
of the turbine will be maintained within
predetermined limits. The compression
20 force of the spring 25 is at all times greater
than the tension of the spring 27. During
normal operation the primary driver will
25 take part of the load and the adjustment of
the governor and the strength of the spring
27 will be such that the turbine will drive
the driven machine at a slightly reduced
speed should the motor fail.

In operation, as the temperature within
the tank or heater *d* rises, the volatile liquid
30 in the bulb 21 develops an increasing vapor
pressure which is transmitted through the
tube 22 to the chamber 23, resulting in ex-
pansion of the diaphragm 24 against the re-
sistance of the spring 25 thereby decreasing
35 the tension of the spring 27 and as this de-
creased tension in the spring 27 is subtracted
from the force of the spring 19 of the main
governor, the speed of the governor will be
40 lowered, and the governor will partly close
the inlet valve, reducing the quantity of
steam passed through the turbine so that
45 the temperature within the tank will fall.
As the temperature within the tank falls,
the pressure within the bulb 21 and the
chamber 23 decreases, resulting in increased
50 tension of the spring 27 which means that
the plunger 16 of the governor is urged
with greater force against the inner ends of
the weighted arms 17 and thus the speed
setting of the governor is raised and a
greater amount of steam will pass through
the turbine.

It is of course, obvious that my invention
is susceptible of various modifications and

changes which are within the spirit of my
invention without departing from the scope
of the following claims, it being understood 55
that the present disclosure of the invention
is by way of illustration only and it is not
to be taken as restrictive of my conception.

What I claim is:—

1. A steam engine, a governor therefor, 60
and means actuated by variations in tem-
perature affected by the relation of the sup-
ply and demand for exhaust steam to ad-
just the speed setting of the governor.

2. A steam engine, a governor therefor, 65
and means actuated by variations in tem-
perature of a substance heated by exhaust
steam from the engine to adjust the speed
setting of the governor.

3. In combination with a driven member, 70
a steam engine driving that member, and a
governor therefor, of means actuated by
variations in temperature affected by the re-
lation of the supply and demand for exhaust
75 steam to adjust the speed setting of the
governor.

4. In combination with a driven member,
a steam engine driving that member, and 80
a turbine therefor, of a temperature respons-
ive device affected by variations in tempera-
ture of a substance heated by the exhaust
steam to adjust the speed setting of the
governor.

5. In combination with a driven mem-
ber, a steam engine and a second driver, all 85
connected to rotate together when either the
second driver or steam engine is driving,
said steam engine having a governor, of
means actuated by variations in temperature
affected by the relation of the supply and 90
demand for exhaust steam to adjust the speed
setting of said governor.

6. In combination with a driven member,
a steam engine driving that member and 95
a second driver, all connected to rotate to-
gether when either the second driver or
steam engine is driving, said steam engine
having a governor, of temperature respons-
ive means actuated by variations in tem-
perature of a substance heated by the ex- 100
haust steam to adjust the speed setting of
said governor.

MAYNARD D. CHURCH.
